UNITED STATES PATENT OFFICE.

HARRY H. HOOD, OF CHICAGO, ILLINOIS, ASSIGNOR TO SPRAGUE CANNING MACHINERY COMPANY, OF CHICAGO, ILLINOIS, A CORPORATION OF ILLINOIS.

CAN-FILLING MACHINERY.

1,261,535.

Specification of Letters Patent. Patented Apr. 2, 1918.

Application filed July 9, 1914. Serial No. 849,941.

To all whom it may concern:

Be it known that I, HARRY H. Hood, a citizen of the United States, residing at Chicago, in the county of Cook and State 5 of Illinois, have invented certain new and useful Improvements in Can-Filling Machinery, of which the following is a specification.

My invention relates to filling machines 10 and particularly to machines adapted for automatically filling cans or other receptacles with comminuated, granular or other finely divided materials such as food stuffs.

The object of the invention is the provision of means acting upon the material supplied thereto in bulk to feed the same in a substantially continuous manner to the receptacles in an automatically gaged amount and to fill the material into the receptacles 20 in measured quantities, thereafter applying a clostire to the receptacle preliminary to the final sealing; the invention including means for automatically positioning the empty receptacles and removing the same 25 when filled.

In order that the invention as hereinafter more fully described and particularly claimed may be clearly understood by those skilled in the art, I have in the accompanying drawings illustrated a preferred embodiment of the invention. In these drawings,

Figure 1 is a side elevation of such a machine;

Fig. 2 is a fragmentary end view of that portion of the machine shown at the right in Fig. 1;

Fig. 3 is a detail of the adjustment mechanism;

Fig. 4 is a vertical longitudinal section on the line 4—4 of Fig. 5;

Fig. 5 is a top plan view of the feeding machine;

Fig. 6 is a vertical section through the filling machine;

Figs. 7, 8, and 9 are transverse sections through Fig. 6 on the lines 7—7, 8—8, and 9—9 respectively;

Fig. 10 is a vertical section on the line 50 10—10 of Fig. 1;

Fig. 11 is a horizontal section on the line 11—11 of Fig. 6;

Fig. 12 is a vertical section through the can feed on the line 12—12 of Fig. 13;

Fig. 13 is a similar section on the line 55 13—13 of Fig. 12, and

Fig. 14 is a fragmentary view of a transmission device.

In these drawings wherein similar reference numerals indicate corresponding parts 60 throughout, 11 designates a hopper which, regardless of its shape, constitutes a container for the material to be operated upon. This hopper is in communication at its lower end with a tube 12, which in the embodiment shown, is deflected from a vertical position at 13 to a horizontal position at 14, the length of the tube is interrupted at 15 and is continued again at 16 as a tube section 17 of similar bore. The gap at 18 70 is bridged by a sleeve 19 which is slidably mounted upon the tube sections for a purpose to be later described.

Within the lower cylindrical portion of the hopper 11 a plunger 20 is mounted for 75 vertical reciprocation by means of a plunger rod 21 having fixed upon its upper end the cross head 22 and slidably mounted upon its medial portion is another cross head 23. A set collar 24 is fixed upon the 80 rod 21 and about the rod is arranged a helical spring 25 bearing upwardly against the lower face of the collar 24 and seated below within the upper surface of the cross head 23. A pair of springs 26, 26 connects the 85 ends of the two cross heads and connecting rods 27, 27 couple the outer ends of the cross head 23 with the crank pins 28 on the gears 29 which are driven by means of pinions 30, 30 upon the shaft 31 carrying the fly 90 wheel 32 and driven by means of the sprocket 33 and chain 34 from the sprocket wheel 35 on the drive shaft 36.

The sleeve 19, above referred to, is provided with trunnions 37, 37 engaged by the 95 arms 38 of a yoke having a stem 39 pivoted upon a crank pin 40 which is adjustably mounted in the slot 41 upon the side face of the cam 42. This cam is fixed upon a shaft 43 driven by means of the large gear 100 44 from the pinion 45 carried by the drive shaft 36.

Rigidly secured to and carried by the reciprocatory sleeve 19 is a cylindrical hous-

ing 46 the axis of which lies outside the sleeve 19. This housing incloses a disk 47 arranged concentrically within the housing and provided eccentrically thereof with an opening 48 of a diameter substantially corresponding to that of the interior of the sleeve. One wall of the opening is formed as a knife edge 49. The disk 47 is mounted upon an oscillatory shaft 50 in such manner as to slide longitudinally thereon but to be fixed against angular movement with reference thereto. This mounting may be advantageously accomplished by providing the shaft 50 with an angular portion 51 and mounting the disk thereon as shown. The oscillatory shaft 50 is provided at one end with an arm 52 connected by a link 53 with an arm 54 of a rock shaft 55 having another arm 56 which travels in the groove 57 of the cam 42.

The operation of the machine as thus far described is as follows: The material, such for instance as corn beef, is supplied to the hopper 11 and by the reciprocating plunger 20 is forced into and through the tube 12. The actuation of the plunger 20 is a yielding one as the positive movement of the cross head 23 is transmitted by means of the springs 26 to the cross head 22 so that the plunger 20 is yieldingly coupled to the cross head 23 and acts upon the material within the tube 12 to force the same forward under yielding pressure depending upon the resistance of the springs 26. If, for instance, the material within the tube 12 is for any reason halted in its passage therethrough the resistance offered by the same to the descent of the plunger 20 will cause the entire movement of the cross head 22 to be taken up by the springs 26, the cross head 22 and the plunger 20 remaining stationary.

The material is fed forward through the section 14 of the tube 12 into the chamber at 18. By means of the cam 42 and its connections with the oscillatory shaft 50 the disk 47 is oscillated until the opening 48 is in register with the interior of the sleeve which incloses the chamber 18, and the sleeve, housing and disk are thereupon moved to the right by means of the yoke 38, the material within the chamber 18 presenting no obstacle to the movement of the disk by reason of the opening 48 being in register with said chamber. When the sleeve, housing and disk have reached a position to the extreme right, the disk is oscillated through the shaft 50 to bring the opening 48 out of register with the chamber 18, the knife edge 49 cutting through the mass of material within said chamber at the point 15. The sleeve is thereupon moved to the left together with the housing and disk and as the opening in the disk is now out of register with the chamber and an im-

the chamber the material within the latter in front of the disk is forced to the left into the tube section 17. The length of feeding stroke of the disk is readily controlled by means of the adjustable crank pin 40 by 70 which the yoke stem is connected to the cam. Preferably the driving of the sleeve and the oscillation of the disk are timed to correspond to the actuation of the cross head 23, so that as the disk moves to the left the 75 material is fed forward behind said disk so as to maintain the chamber full. Each reciprocation of the sleeve and disk serves to force the material in front of the disk forward through the constricted bore of the 80 tube 17 to the filling machine proper.

In the frame 58 is mounted a vertical main shaft 59 carrying a crown gear 60 in mesh with a bevel gear 61 upon a shaft 62 carrying a fly wheel 63 and driven by a sprocket 85 64 and chain 65 from a sprocket 66 on the shaft 43. The main shaft 59 has keyed thereon a rotary table 67 provided near its periphery with a series of openings 68 within each of which is mounted for vertical 90 reciprocation a sleeve or pocket 69 adapted to receive the cans 70 and position the same for filling. The opposite walls of the pockets are provided with vertical slots 71, the movement of the pockets being guided 95 thereby upon bolts 72 extending diametrically across the pockets and seated in the flanges of the table. Within each of the pockets is arranged a core 73 upon the standard 74 mounted upon the bolt 72 by 100 means of a slot 75 so as to permit of slight vertical movement. In its lowermost position the upper face of the core 73 is flush with the upper face of the table 67 and is capable of elevation above the face of the 105 table for a slight distance limited by the slot 75.

At one side of the shaft 59 and immediately below the standard 74 is arranged the vertically movable plunger 76 which 110 carries a roller 77 traveling within the groove 78 of a cam 79 keyed to the main shaft 59, the purpose of the plunger when actuated by the cam being to elevate the core 73 for a purpose hereafter to be explained. 115

A drive pinion 80 is fixed upon the shaft 59 in mesh with the transmission pinion 81 which in turn meshes with a driven pinion 82 fixed upon the shaft 83 having upon its lower end a crank disk 84 carrying an eccentrically mounted roller 85 for the driving of the Geneva gear wheel 86 by the successive engagement of the roller 85 with the notches 87 of said gear, the shaft 83 being notched out at 88 in the plane of the 120 gear 86 to permit the passage in turn of the teeth 89 by way of the notched-out portion and then to lock said gear by the engagement of the shaft within the notches 90 of the gear. A detent 91 actuated by the 125 gear 86 locks the gear 86 in position. A 130

spring 92 snaps into engagement with the notches 93 to more accurately hold the table 67 during the intervals between the actuation of the Geneva gear, the purpose of this 5 gear being to move the can holding pockets 69 forward step by step to receive the cans and to position the same beneath the filling tube, and then to discharge the same one by one from the machine.

10 Above the table 67 and the gears 80, 81 and 82 there is mounted upon the main shaft 59 a cylindrical mutilated gear 94 which is smooth throughout its periphery with the exception of a limited area and 15 preferably, as shown, about one-sixth thereof being toothed at 95. Alongside the gear 94 is a cylinder 96 mounted upon the shaft 97 and having its periphery divided into twelve divisions, each alternate division being toothed at 98 to engage with the teeth 95 of the gear 94 while the intermediate alternate portions are concaved as shown at 99 to snugly fit the untoothed portion of the gear 94 in a complementary manner 20 whereby during the time that the smooth portions of the two gears are in contact the cylinder 96 is locked against movement by the gear 94. The cylinder 96 is also held stationary at such times by means of a locking dog 100 formed as a toothed rack in mesh with the toothed segment 101 fixed upon a shaft 102 having an arm 103 connected by means of a link 104 with the arm 105 of a slide 106 reciprocated within the 25 guide 107 by means of a groove 108 in the lower face of the cam 109 engaging a roll 110 mounted upon said slide.

The cylinder 96 is provided with six 30 equally spaced longitudinally extending chambers 111, which in succession are brought into register above with the discharge end 112 of the tube 113 connected to the feeding tube 17, and below into register with a vent pipe 114 guarded by a finely 35 perforated vent plate 115.

40 Upon the upper end of the main shaft 59 is mounted, as before stated, a cam 109. This cam is provided with a peripheral cam groove 116 within which travels a roller 117 45 mounted upon the head 118. This head has mounted upon its inner face a pair of pinions 119, 119 which are in mesh exteriorly with two opposed stationary toothed racks 120, 120, and interiorly in mesh with doubly 50 racked bar 121 formed in its lower portion as a plunger 122, whereby the throw of the cam groove 116 is imparted in a double degree to the said plunger 122, which plunger 55 is in vertical alinement with one of the 60 chambers 111 at the same time that another of the chambers is in register with the feeding tube and while the cylinder 96 is stationary as before described.

Immediately above the cylinder 96 and 65 contiguous to the upper face thereof is a

cap feeding plate 123 within which and immediately beneath the open bottom of the cap magazine 124 operates a slide 125 by which the caps 124 are transferred one by one from the magazine to a position above 70 that one of the chambers 111 which is in alinement with the plunger 122. This slide is intermittently actuated by means of the slide 106 previously described, an arm 126 of the same being connected to the lever 127 75 and the lever in turn being connected by the rod 128 with said slide, a spring 129 being interposed to form a yielding connection.

Upon the lower portion of each of the pockets 69 are mounted pins 130 each carrying a pair of rollers 131 and 132. The rollers 131 are arranged to travel upon a track comprising a depressed portion 133 and an elevated portion 134 connected by an incline 135. When traveling upon the 80 depressed portion of the track the pockets occupy the position shown at the left hand in Fig. 6, their upper edges being flush with the top of the table. As the roller 131 travels up the incline the pockets are elevated gradually to correspond to the pitch of the incline until they reach the elevated portion 134 when they occupy the position shown at the right hand in said Fig. 6 and extend considerably above the upper face 85 of the disk so as to receive and position accurately the cans 70 beneath that chamber 111 which is in alinement with the plunger 122. At this time also the cam 79 operates to force the roller 131 upwardly against the 90 standard 74 to lift the can and press the top of the same firmly against the plate 136 which is supported by the springs 137 so as to effect a tight joint between the can and the chamber.

100 After passing this point the rollers 132 engage beneath the overhanging track 138 to positively lower the pocket 69 as it descends the incline on the opposite side so as to leave the filled can 70 in position to 105 be wiped off the table or removed in any suitable manner.

Immediately after the pocket 69 reaches the upper level 134 and is thus elevated above the table 67 it is brought beneath the 115 lower open end of a can chute 139 formed of the four angle bars 140, one at each corner, within which the cans 70 fit. At the mouth of the chute are disposed a pair of inwardly inclined spring clips 141 which serve to 120 press against the sides of the can and frictionally retard the descent of the same. Immediately above the spring clips 141 are disposed a pair of blocks 142, 142 inwardly pressed by means of the bow spring 143, 125 the ends of which are removably seated in the blocks, as shown at 144. The inner faces of these blocks downwardly converge as shown in Fig. 12. Upon the other two sides of the chute are arranged a pair of oppo- 130

sitely disposed spring arms 145 carried by a yoke 146 upon a rod 147, the upper end of which is secured to the head 118 so that the spring arms 145 move in unison with the said head. The lower ends of the arms 145 are adapted to engage over the upper edge of a can and force the same downwardly between the yielding blocks 142 and the clips 141 discharging the same from the open 10 lower end of the chute into that pocket 69 which is positioned beneath the same, the spring arm 145 retreating upwardly to engage the next can which is frictionally held by the blocks 142.

15 The operation of this portion of the machine is as follows: As the material is supplied from the discharge end 112 of the feeding machine into that one of the chambers 111 which is in register therewith the 20 chamber is completely filled under pressure from the reciprocating disk 47, the air being discharged from said chamber through the perforated vent plate 115 and the vent pipe 114, the cylinder 96 being at this time stationary. The constantly rotating gear 94 now engages with its teeth 95 the teeth 98 of the said cylinder 96 and causes the rotation of the latter through one-sixth of a revolution when the cylinder 96 again comes to rest 25 with the next chamber 111 beneath the feed discharge 112. At this moment the disk 47 is reciprocated and another charge of material is forced through the pipe 17 and the discharge 112 into the chamber placed ready 30 to receive it. As the cylinder 96 is again actuated that chamber first filled is brought to a position in vertical alinement with the 35 plunger 122 and with a can 70 held within a pocket 69 against the plate 136. The cap feeding slide 125 transfers the bottom cap on the magazine 124 to a position immediately beneath the plunger 122, and this plunger is then actuated in unison with the disk 47 so that while one of the chambers 40 45 being charged from the feeding tube 112 the plunger 122 descends carrying with it the cap, preferably of paste board, and forcing the charge of the chamber 111 ahead of said cap into the can upon the core 73 below said chamber. The cap is slightly larger than the plunger 122 and the chamber 111 so that it is upwardly cupped and reduced to the 50 size of the can opening. The plunger forces the cap into the can on top of the material 55 and the cupped edge of the cap expands so as to prevent its dislodgment therefrom. This cap forms a temporary closure for the can until the permanent closure can be soldered in place.

60 When the plunger 122 has retreated upwardly the table 67 is by the Geneva gear again actuated to bring another can into filling position and the cylinder 96 is actuated by the gear 94 to bring other chambers 65 in line with the feed tube 112 and the plunger

122. As the pocket with the filled can leaves its position beneath the plunger 122 the track 138 engages over the roller 132 and assists the action of gravity in lowering the pocket 69 upon the incline 135 so as to leave 70 the can sitting upon the face of the table and free to be swept therefrom on to a conveyor or otherwise removed in a suitable manner.

It will be observed that the operation of 75 the machine is entirely automatic, the material being fed by means of the plunger 20 and its yielding driving mechanism in amount gaged by the demand of the filling machine proper until the material reaches 80 the chamber 18, and from thence it is positively fed, being forced by the disk 47 in accurately measured quantities sufficient at each feeding impulse to supply one of the chambers 111 of the cylinder 96. Moreover, 85 to 90 the operation of the parts is so timed that they severally cooperate in synchronism each to perform its own function and contributing to the joint operation of the machine as a whole.

While I have herein shown and described with a considerable degree of particularity a preferred embodiment of the invention illustrating and describing in detail the construction, arrangement and operation of the 95 various parts it will be understood that considerable modification may be resorted to without departing from the essence of the invention or sacrificing its material advantages.

I claim:

1. In a can filling machine, the combination with a feeding device, a delivery tube leading therefrom, the tube provided with a gap, a sleeve bridging the gap and slidable on the tube, a housing carried by the sleeve, a disk within the housing and having an eccentrically disposed opening, means to oscillate the disk to bring the opening into and out of register with the sleeve interior, and means to reciprocate the sleeve upon the delivery tube, substantially as described.

2. In a filling machine, the combination with a feeding device, of a delivery tube leading therefrom, the tube provided with a gap, a sleeve bridging the gap and slidable on the tube, a housing eccentrically mounted on the sleeve and moving therewith, a disk within the housing and having an eccentrically disposed opening with a knife edge, means to oscillate the disk to bring the opening into and out of register with the sleeve interior, said means comprising a rock shaft having an engagement with the disk to permit longitudinal and prevent lateral relative movement of the shaft and disk, means to rock the shaft, and means to reciprocate the sleeve upon the tube in alternation with the oscillation of the disk, substantially as described.

3. In a filling machine, the combination with a feeding device, of a delivery tube leading therefrom, the tube provided with a gap, a sleeve bridging the gap and slidable 5 on the tube, a housing eccentrically mounted on the sleeve and moving therewith, a disk within the housing and having an eccentrically disposed opening with a knife edge, means to oscillate the disk to bring the opening into and out of register with the sleeve interior, said means comprising a rock shaft having an angular portion engaging an angular opening centrally of the disk to permit 10 longitudinal and prevent angular relative movement of the shaft and disk, an arm carried by the shaft, a cam acting on the rock shaft arm to oscillate the shaft and with it the disk, and means to reciprocate the sleeve upon the delivery tube, said means 15 comprising a yoke connected to said sleeve and a crank connected to the yoke, substantially as described.
4. In a filling machine, the combination with a feeding device, of a delivery tube 20 leading therefrom, the tube provided with a gap, a sleeve bridging the gap and slidable on the tube, a housing eccentrically mounted on the sleeve and moving therewith, a disk within the housing and having an eccentrically disposed opening with a knife edge, means to oscillate the disk to bring the opening into and out of register with the sleeve interior, said means comprising a rock shaft having an angular portion engaging an angular opening centrally of the disk to permit 25 longitudinal and prevent angular relative movement of the shaft and disk, an arm carried by the shaft, a cam acting on the rock shaft arm to oscillate the shaft and with it the disk, and means to reciprocate the sleeve upon the delivery tube, said means comprising a yoke connected to said sleeve and a crank connected to the yoke, substantially as described.
5. In a can filling machine, the combination of a hopper, a delivery tube leading therefrom, a plunger mounted to reciprocate 30 within the hopper in line with the tube, means to yieldingly reciprocate the plunger, the tube provided with a gap, a sleeve bridging the gap and slidable on the tube, a housing carried by the sleeve, a disk within the housing and having an eccentrically disposed opening, means to oscillate the disk to bring the opening into and out of register with the sleeve interior, and means to reciprocate the sleeve upon the delivery tube, 35 substantially as described.
6. In a can filling machine, the combination of a hopper, a delivery tube leading therefrom, a plunger mounted to reciprocate within the hopper in line with the tube, a cross head fixed on the plunger, driving 40 means, a yielding connection between the driving means and the cross head, the tube provided with a gap, a sleeve bridging the gap and slidable on the tube, a housing eccentrically mounted on the sleeve and moving therewith, a disk within the housing and having an eccentrically disposed opening with a knife edge, means to oscillate the disk to bring the opening 45 into and out of register with the sleeve interior, said means comprising a rock shaft having an angular portion engaging an angular opening centrally of the disk to permit longitudinal and prevent angular relative movement of the shaft and disk, an arm carried by the shaft, a cam acting on the rock shaft arm to oscillate the shaft and with it the disk, and means to reciprocate the sleeve upon the delivery tube, said means comprising a yoke connected to said sleeve and a crank connected to the yoke, substantially as described.
7. In a can filling machine, a main shaft, a drive pinion thereon, a driven pinion, an intermediate transmission pinion, a shaft 50 carrying the driven pinion, a Geneva gear driven by the said shaft, a rotary table rotating with the said gear and provided with can pockets, and means to deliver the material intermittently to a point adjacent the open mouths of the cans in the pockets, substantially as described.
8. In a can filling machine, a main shaft, a drive pinion thereon, a driven pinion, an intermediate transmission pinion, a shaft 55 carrying the driven pinion, a Geneva gear driven by said shaft, a table rotating with said gear and provided with openings, can pockets mounted to reciprocate within the openings, means to deliver the material to the cans within the pockets when the pockets are in their elevated position, and means to depress the pockets in order to release the cans, substantially as described.
9. In a can filling machine, a main shaft, a drive pinion thereon, a driven pinion, an intermediate transmission pinion, a shaft 60 carrying the driven pinion, a Geneva gear driven by said shaft, a table rotating with the said gear and provided with spaced concentric openings, cores within the openings, can pockets mounted to reciprocate vertically within the openings about the cores, means to feed the cans to the pockets on the cores, means to deliver the material to a point above the open mouth of a can in a pocket, and means to elevate the cores to press the can against the mouth of the material delivery, substantially as described.
10. In a can filling machine, a main shaft, 65

5 a drive pinion thereon, a driven pinion, an intermediate transmission pinion, a shaft carrying the driven pinion, a crank disk mounted on the shaft, a notched gear arranged to be engaged by the crank and intermittently rotated thereby, a rotary table rotating with the said gear and provided with can pockets, and means to deliver the material intermittently to a point adjacent 10 the open mouths of the cans in the pockets, substantially as described.

11. In a can filling machine, a main shaft, a drive pinion thereon, a driven pinion, an intermediate transmission pinion, a shaft 15 carrying the driven pinion, a crank disk mounted on the shaft, a notched gear arranged to be engaged by the crank and intermittently rotated thereby, a table rotating with said gear and provided with openings, can pockets mounted to reciprocate within the openings, means to deliver the material to the cans within the pockets when the pockets are in their elevated position, and means to depress the pockets in 20 order to release the cans, substantially as described.

12. In a can filling machine, a main shaft, a drive pinion thereon, a driven pinion, an intermediate transmission pinion, a shaft 25 carrying the driven pinion, a crank disk mounted on the shaft, a notched gear arranged to be engaged by the crank and intermittently rotated thereby, a table rotating with the said gear and provided with spaced 30 concentric openings, cores within the openings, can pockets mounted to reciprocate vertically within the openings about the cores, means to feed the cans to the pockets on the cores, means to deliver the material to a 35 point above the open mouth of a can in a pocket, and means to elevate the cores to press the can upwardly against the mouth of the material delivery, substantially as described.

13. In a can filling machine, a main shaft, 45 a drive pinion thereon, a driven pinion, an intermediate transmission pinion, a shaft carrying the driven pinion, a Geneva gear driven by said shaft, a table rotating with said gear and provided with spaced openings, can pockets mounted to reciprocate vertically within the openings, a cam track for the pockets whereby to reciprocate the pockets from a position flush with the table to a position above the same, and means to 50 deliver the material to a point above the can pocket when it reaches its elevated position, substantially as described.

14. In a can filling machine, a main shaft, a drive pinion thereon, a driven pinion, an 60 intermediate transmission pinion, a shaft carrying the driven pinion, a Geneva gear driven by said shaft, a table rotating with said gear and provided with spaced openings, can pockets mounted to reciprocate vertically within the openings, a cam track

for the pockets and having depressed and elevated portions whereby to vertically reciprocate the pockets from a position flush with the table surface to a position above the same to surround the cans, a cam track 70 arranged to engage the pockets and return the same to their depressed condition to release the cans, and means to deliver the material to a point above the cans in their elevated position, substantially as described. 75

15. In a can filling machine, a main shaft, a drive pinion thereon, a driven pinion, an intermediate transmission pinion, a shaft carrying the driven pinion, a Geneva gear driven by said shaft, a table rotating with 80 said gear and provided with spaced openings, cores within the openings, can pockets mounted to reciprocate vertically within the openings about the cores, the can pockets provided with rollers, a cam track for the 85 rollers having depressed inclined and elevated portions whereby to guide the pockets from a position flush with the table surface to a position above the same to inclose the cans, a cam track arranged to engage over 90 the rollers to return the pockets to their depressed position to release the cans, means to deliver the material to a point above the cans when the pockets are in their elevated position, and means acting upon the cores to 95 press the cans upwardly against the material delivery, substantially as described.

16. In a can filling machine, the combination with a feeding device, and a delivery tube leading therefrom, of a shaft, a rotary 100 table driven thereby, can pockets carried by the table to revolve therewith, a mutilated gear driven by the shaft, a concentrically chambered cylinder provided with a peripherally mutilated gear coacting with the last 105 named gear to intermittently drive the cylinder step by step, a delivery tube arranged with its mouth immediately adjacent one of the chambers in a position of rest, the path of the chamber axes cutting the path of the 110 can pockets, and means to discharge the material from a chamber into a can at the intersection of their paths of travel, substantially as described.

17. In a can filling machine, the combination with a feeding device, and a delivery tube leading therefrom, of a shaft, a rotary table driven thereby, can pockets carried by the table to revolve therewith, a mutilated gear driven by the shaft, a concentrically 115 chambered cylinder provided with a peripherally mutilated gear coacting with the last named gear to intermittently drive the cylinder step by step, the delivery tube arranged with its mouth immediately above one of the 120 chambers in a position of rest, a vent pipe having its entrance disposed at the opposite end of such chamber, a perforated vent plate at the entrance to the vent pipe, the path of the chamber axes cutting the path of the 125 130

can pockets, means to supply cans to the pockets, and means to discharge the material from a chamber into a can at the intersection of their paths of travel, substantially 5 as described.

18. In a can filling machine, the combination with a feeding device, and a delivery tube leading therefrom, of a shaft, a rotary table driven thereby, can pockets carried by 10 the table to revolve therewith, a mutilated gear driven by the shaft, a concentrically chambered cylinder provided with a peripherally mutilated gear coacting with the last named gear to intermittently drive the cylinder step by step, a delivery tube arranged 15 with its mouth immediately adjacent one of the chambers in a position of rest, the path of the chamber axes cutting the path of the can pockets, and means to discharge the material from a chamber into a can at the intersection of their paths of travel, said means comprising a cam, a plunger operatively connected to the cam to reciprocate in a path intersecting the path of the cylinder chambers 20 and of the can pockets, substantially as described.

19. In a can filling machine, the combination with a feeding device, and a delivery tube leading therefrom, of a shaft, a rotary table driven thereby, can pockets carried by the table to revolve therewith, a mutilated gear driven by the shaft, a concentrically chambered cylinder provided with a peripherally mutilated gear coacting with 30 the last named gear to intermittently drive the cylinder step by step, a delivery tube arranged with its mouth immediately adjacent one of the chambers in a position of rest, the path of the chamber axes cutting 35 the path of the can pockets, and means to discharge the material from a chamber into a can at the intersection of their paths of travel, said means comprising a cam, a head provided with means engaging the cam to reciprocate the head, a pair of pinions mounted on the head, a pair of oppositely facing stationary racks in mesh with the pinions, a slidable double faced rack disposed between and in mesh with the pinions, a plunger connected to the slidable 40 rack to reciprocate in a path intersecting the path of the cylinder chambers and of the can pockets, substantially as described.

20. In a can filling machine, the combination with a feeding device, and a delivery tube leading therefrom, of a shaft, a rotary table driven thereby, can pockets carried by the table to revolve therewith, a mutilated gear driven by the shaft, a concentrically chambered cylinder provided with a peripherally mutilated gear coacting with the last named gear to intermittently drive the cylinder step by step, the delivery tube arranged with its mouth immediately 50 above one of the chambers in a position of

rest, a vent pipe having its entrance disposed at the opposite end of such chamber, a perforated vent plate at the entrance to the vent pipe, the path of the chamber axes cutting the path of the can pockets, means 55 to supply cans to the pockets, and means to discharge the material from a chamber into a can at the intersection of their paths of travel, said means comprising a cam carried by the said shaft, a head provided with a roller engaging the cam to reciprocate the head, a pair of pinions mounted on the head, a pair of oppositely facing stationary racks in mesh with the pinions, a slidable double faced rack disposed between and in 60 mesh with the pinions, a plunger forming a continuation of the slidable rack and guided for reciprocation in a path intersecting the paths of the cylinder chambers and of the can pockets, substantially as described. 65

21. In a can filling machine, the combination with a feeding device, and a delivery tube leading therefrom, of an intermittently actuated rotary table provided with can receiving devices, an intermittently driven cylinder provided with spaced longitudinally extending chambers, a reciprocating plunger, the orbits of the can receiving devices and of the chambers being eccentric to 70 each other and intersecting the path of the plunger, the orbit of the chamber axes also intersecting the axis of the delivery tube adjacent to its mouth, the said rotary members coming to rest at such points of intersection, substantially as described. 75

22. In a can filling machine, the combination with a material-delivery tube, means for yieldingly feeding the material through a portion of said tube, and means receiving 80 the material from the first feeding means and positively feeding the same through the latter portion of the tube in measured quantities, of an intermittently driven rotary table adapted to carry cans or the like, an intermittently driven cylinder provided with spaced chambers, a reciprocating plunger, the orbits of the cans on the rotary table and the chamber axes being eccentric to 85 each other and intersecting the path of the plunger, the orbit of the chamber axes also intersecting the axis of the delivery tube adjacent its mouth, the said rotary members coming to rest at such points of 90 intersection, substantially as described. 95

23. In a device of the class described, a receptacle, a delivery tube leading therefrom, said tube having a gap, a sleeve bridging the gap and slidable on the tube, means for opening and closing the passage through 100 said sleeve, and means for reciprocating said sleeve on said tube. 105

24. In a device of the class described, a receptacle, a delivery tube leading therefrom, said tube having a gap, a sleeve bridg- 110

ing the gap and slidable on the tube, means for opening and closing the passage through said sleeve, means for reciprocating said sleeve on said tube, and yielding means for 5 forcing the material from said receptacle to said tube.

25. In a device of the class described, a receptacle, a delivery tube leading therefrom, said tube having a gap, a sleeve bridging the gap and slidable on the tube, means for opening and closing the passage through said sleeve, means for reciprocating said sleeve on said tube, yielding means for forcing the material from said receptacle to 10 said tube, comprising a plunger, and means for reciprocating said plunger in time with said sleeve.

26. A filling machine comprising a plunger, a rotatable member having a plurality 20 of passages therethrough movable successively into the path of said plunger whereby said plunger may enter said passages and force the material therefrom, means for supplying material to said passages, and means 25 for preventing the material from escaping from those passages not in registration with said plunger, said supply means comprising a supply conduit with which said passages successively register, said preventing means 30 comprising a perforated guard with which the passage in registry with the supply passage registers to permit the escape of air and prevent the escape of the supplied material.

35. 27. In a device of the class described, a receptacle, a delivery tube leading therefrom, said tube having a gap, a sleeve bridging the gap and slidable on the tube, means for opening and closing the passage through 40 said sleeve, and means for reciprocating said sleeve in said tube, a plunger, a rotatable member having a plurality of receptacles therein movable successively into the path of said plunger, whereby said plunger may 45 enter said receptacles to force the material therefrom, said receptacles being successively movable into communication with said delivery tube.

28. In a device of the class described, a 50 receptacle, a delivery tube leading therefrom, said tube having a gap, a sleeve bridging the gap and slidable on the tube, means for opening and closing the passage through said sleeve, means for reciprocating said 55 sleeve in said tube, and yielding means for forcing the material from said receptacle to said tube, a plunger, a rotatable member having a plurality of receptacles therein movable successively into the path of said 60 plunger whereby said plunger may enter said receptacles to force the material therefrom, said receptacles being successively movable into communication with said delivery tube.

65. 29. In a device of the class described, a

receptacle, a delivery tube leading therefrom, said tube having a gap, a sleeve bridging the gap and slidable on the tube, means for opening and closing the passage through said sleeve, means for reciprocating said 70 sleeve in said tube, a plunger, a rotatable member having a plurality of receptacles therein movable successively into the path of said plunger, whereby said plunger may enter said receptacles to force the material 75 therefrom, said receptacles being successively movable into communication with said delivery tube, and means for moving a can into position to receive the material forced out by said plunger. 80

30. In a device of the class described, a receptacle, a delivery tube leading therefrom, said tube having a gap, a sleeve bridging the gap and slidable on the tube, means for opening and closing the passage through 85 said sleeve, means for reciprocating said sleeve in said tube, a plunger, a rotatable member having a plurality of receptacles therein movable successively into the path of said plunger, whereby said plunger may 90 enter said receptacles to force the material therefrom, said receptacles being successively movable into communication with said delivery tube, means for moving a can into position to receive the material forced 95 out by said plunger, and means for supplying a can closure in the path of said plunger.

31. In a filling machine, a feed mechanism comprising a passage for receiving and discharging material, a first yielding 100 feed mechanism for yieldingly pressing the material into said passage, a second positive intermittent feed mechanism for intermittently advancing the entire quantity of material traversing the passage, to discharge a definite, predetermined amount of material from said passage, and supply mechanism for bringing receptacles into position to be filled. 105

32. In a filling machine, a feed mechanism comprising a passage for receiving and discharging material, a first intermittent, yielding feed mechanism for intermittently and yieldingly pressing the material into said passage, a second positive intermittent feed mechanism for intermittently advancing the entire quantity of material traversing the passage to discharge a definite, predetermined amount of material from said passage, driving means for operating said feed mechanisms in time with each other, so that said first feed mechanism is pressing material into the passage at the same time the second feed mechanism is advancing the material in said passage, and 120 supply mechanism for bringing receptacles into position to be filled. 125

33. In a filling machine, a feed mechanism comprising a passage for receiving and discharging material, a first yielding 130

- feed mechanism for yieldingly pressing the material into said passage, a second positive intermittent feed mechanism for intermittently advancing the entire quantity of material traversing the passage, to discharge a definite, predetermined amount of material from said passage, and supply mechanism for bringing receptacles into position to be filled, the portion of said passage between the discharge portion and said second feed mechanism being of less capacity than the portion of said passage between said feed mechanisms.
34. In a filling machine, a feed mechanism comprising a passage for receiving and discharging material, a first intermittent, yielding feed mechanism for intermittently and yieldingly pressing the material into said passage, a second positive intermittent feed mechanism for intermittently advancing the entire quantity of material traversing the passage to discharge a definite, predetermined amount of material from said passage, driving means for operating said feed mechanisms in time with each other, so that said first feed mechanism is pressing material into the passage at the same time the second feed mechanism is advancing the material in said passage, and supply mechanism for bringing receptacles into position to be filled, said first feed mechanism comprising a reciprocating plunger operating in said passage.
35. In a filling machine, a feed mechanism comprising a passage for receiving and discharging material, a first intermittent, yielding feed mechanism for intermittently and yieldingly pressing the material into said passage, a second positive intermittent feed mechanism for intermittently advancing the entire quantity of material traversing the passage to discharge a definite, predetermined amount of material from said passage, driving means for operating said feed mechanisms in time with each other, so that said first feed mechanism is pressing material into the passage at the same time the second feed mechanism is advancing the material in said passage, and supply mechanism for bringing receptacles into position to be filled, said first feed mechanism comprising a reciprocating plunger operating in said passage, said second feed mechanism comprising a feed member reciprocating in time with said plunger.
36. In a filling machine, a feed mechanism comprising a passage for receiving and discharging material, a first yielding feed mechanism for yieldingly pressing the material into said passage, and a second positive intermittent feed mechanism for intermittently advancing the entire quantity of material traversing the passage, to discharge a definite, predetermined amount of material from said passage.
37. In a filling machine, a feed mechanism comprising a passage for receiving and discharging material, a first yielding feed mechanism for yieldingly pressing the material into said passage, and a second positive intermittent feed mechanism for intermittently advancing the entire quantity of material traversing the passage, to discharge a definite, predetermined amount of material from said passage.
38. In a filling machine, a feed mechanism comprising a passage for receiving and discharging material, a first intermittent yielding feed mechanism for intermittently and yieldingly pressing the material into said passage, a second positive intermittent feed mechanism for intermittently advancing the entire quantity of material traversing the passage, to discharge a definite, predetermined amount of material from said passage, and driving means for operating said feed mechanisms in time with each other so that said first feed mechanism is pressing material into the passage at the same time the second feed mechanism is advancing the material in the passage.
39. In a filling machine, a feed mechanism comprising a passage for receiving and discharging material, a first yielding feed mechanism for yieldingly pressing the material into said passage, and a second positive intermittent feed mechanism for intermittently advancing the entire quantity of material traversing the passage, to discharge a definite, predetermined amount of material from said passage, the portion of said passage between the discharge portion and said second feed mechanism being of less capacity than the portion of said passage between said feed mechanisms.
40. In a filling machine, a feed device comprising a passage for receiving and discharging material, a first intermittent yielding feed mechanism for intermittently and yieldingly pressing the material into said passage, a second positive intermittent feed mechanism for intermittently advancing the entire quantity of material traversing the passage, to discharge a definite, predetermined amount of material from said passage, and driving means for operating said feed mechanisms in time with each other so that said first feed mechanism is pressing material into the passage at the same time the second feed mechanism is advancing the material in said passage, said first feed mechanism comprising a reciprocating plunger operating in said passage.
41. In a filling machine, a feed device comprising a passage for receiving and discharging material, a first intermittent yielding feed mechanism for intermittently and yieldingly pressing the material into said passage, a second positive intermittent feed mechanism for intermittently advancing the entire quantity of material traversing the passage, to discharge a definite, predetermined amount of material from said passage.

entire quantity of material traversing the passage, to discharge a definite predetermined amount of material from said passage, and driving means for operating said feed mechanisms in time with each other so that the first feed mechanism is pressing material into the passage at the same time the second feed mechanism is advancing the material in said passage, said first feed mecha-

nism comprising a reciprocating plunger operating in said passage, said second feed mechanism comprising a feed member reciprocating in time with said plunger. ¹⁰
